ELECTRICAL SWITCH

Nelson Frederick John Godfrey, Leighton Buzzard, England, assignor to ERG Industrial Corporation Limited, Dunstable, England

Filed May 4, 1973, Ser. No. 357,149

Claims priority, application Great Britain Feb. 23, 1973

Term of patent 14 years

Int. Cl. D13—03

U.S. Cl. D26—13 R

FIG. 2

FIG. 3

FIG. 4

FIG. 5

FIG. 6

FIG. 8

FIG. 10

FIG. 1 is a perspective view of the top, front and one end of an electrical switch showing my new design;

FIG. 2 is a top plan view thereof;

FIG. 3 is a rear elevational view thereof;

FIG. 4 is a bottom plan view thereof;

FIG. 5 is an end elevational view thereof looking in the direction of arrow 5 in FIG. 1;

FIG. 6 is an end elevational view thereof looking in the direction of arrow 6 in FIG. 1;

FIG. 7 is a perspective view of the top, front and one end of an electrical switch showing a second embodiment of my new design;

FIG. 8 is a rear elevational view of the embodiment shown in FIG. 7;

FIG. 9 is a perspective view of the top, front and one end of an electrical switch showing a third embodiment of my new design; and

FIG. 10 is a rear elevational view of the embodiment shown in FIG. 9.

The undisclosed bottom and ends of the embodiments shown in FIGS. 7 and 9 are substantially the same as the bottom shown in FIG. 4, and ends shown in FIGS. 5 and 6.

I claim:

The ornamental design for an electrical switch, substantially as shown and described.
